UNITED STATES PATENT OFFICE.

ANNA M. LAPHAM, OF ST. PAUL, MINNESOTA.

PARCEL CARRIER FOR SHOPPERS.

Application filed June 13, 1924. Serial No. 719,802.

This invention relates to parcel carriers especially adapted to the use of shoppers.

It is the object of the invention to provide a simple but highly efficient parcel carrier especially adapted for use by women, which may be either carried on the arm, as a shopping bag, or, when filled with parcels, pulled or pushed along the ground.

It is a more specific object to provide in such a device a flat wheeled frame, having a collapsible parcel receptacle, detachably mounted thereon.

These and other objects of the invention will be apparent from the following description made in connection with the drawings, in which like reference characters refer to similar parts throughout the several views, and, in which

Fig. 1 is a front elevation with some portions broken away.

Fig. 2 is a cross section taken on the line 2-2 of Fig. 1.

Fig. 3 is an enlarged rear elevation of the detachable means for connecting the upper end of the parcel receptacle to the frame, and

Fig. 4 is a similar enlarged detail view of the detachable securing means for the bottom of the parcel receptacle.

A rectangular skeleton frame 5 preferably constructed of wire includes a transverse bottom member 6, preferably twisted at its end about the longitudinal side members 5^a. The frame 5 at its top is bent to form an upwardly projecting handle 7 and loops 8 at both upper corners thereof.

The bottom ends of the longitudinal side portions 5^a of the frame are projected below and beyond the transverse bottom member 6 and bent inwardly at right angles to form a pair of stub axles 9, which are mounted on a pair of small, preferably rubber-tired wheels 10.

A flexible rectangular receptacle or parcel bag 11 preferably of the expandable type is detachably secured to and within the frame 5 in the following manner:

Small straps 12, equipped with snap buttons 12^a are stitched or otherwise secured to the upper corners of the rectangular parcel bag on the rear side thereof. These straps 12 are adapted to be inserted through the loops 8 on the top corners of frame 5 and the snap buttons 12^a secured thereby supporting the parcel receptacle 11 from the top of the frame.

At the bottom corners of receptacle 11 a pair of flexible loops 13 are stitched or otherwise secured, which loops are adapted to be slipped over a pair of hooks preferably formed in the end portions of the transverse bottom members 6. In mounting the stub axles 9 on the wheels 10 a pair of small burrs 15 are preferably used on each wheel, one at either side thereof, to provide proper bearing shoulders therefor.

The extreme ends of the axles 9 are threaded to engage the outer burr thereby properly securing the wheels to the axles.

The parcel receptacle 11 shown is provided with a large expandable covered pocket 11^a and a smaller outside pocket 11^b, which pockets will accommodate a good size load of bundles.

Since the entire device is very light and of thin cross section it may be easily carried on the shopper's arm, while the articles are being purchased, and when filled may be dragged along the ground supported on its wheels 10.

The device is of sufficient height to extend from the ground to the hands of the shopper so that the carrier is normally disposed in upright position when loaded and in use. Because of its thin cross section and its normal upright position it will take up little room when dragged thru a crowded street or store, and will consequently not interfere with pedestrians or other shoppers.

Receptacle 11 may be quickly removed for cleaning or repair.

Where the ordinary shopping bag is used the entire weight of the packages purchased must be carried by the shopper. Thus, a housewife is heavily burdened and considerably fatigued if she has a number of purchases to make.

Considerable actual usage of this invention has proven it highly successful for the purposes intended. It not only relieves the shopper from the weight of the heavy load of bundles but also permits the purchases to be made and brought home in less time without danger of breakage on the way.

It is to be understood that considerable changes in the form, details and arrangement of parts may be made without departing from the scope of applicant's invention, and that the use of the device is to be by no means limited to a parcel carrier for shoppers but may be extended to every reasonable use to which it may be put.

What is claimed is:

1. A parcel carrier for shoppers having in combination a skeleton frame including a single elongated strip of material formed in the shape of an inverted U, the upper corners of said strip being twisted to constitute loops, ground engaging supporting members mounted on the lower ends of said strip and a flexible parcel receptacle mounted within said frame having means at its upper end adapted to engage said loops to stretch and support said receptacle in operative position.
2. The structure set forth in claim 1, a transverse reinforcing member secured be-

tween the sides of said U-shaped member adjacent the lower ends of said sides and means for securing the bottom ends of said receptacle to said reinforcing member. 15

3. A parcel carrier for shoppers comprising a flat skeleton frame having a handle at its upper end and having its longitudinal sides projected and bent inwardly to form a pair of stub axles, a wheel rotatably secured to each of said axles so formed, and a parcel receptacle secured to said frame. 20 25

In testimony whereof I affix my signature.

ANNA M. LAPLHAM.
